UNITED STATES PATENT OFFICE.

JOHN WARREN SMITH AND GEORGE UPTON HARN, JR., OF COLUMBUS,
OHIO.

PRINTING-ROLL.

SPECIFICATION forming part of Letters Patent No. 747,096, dated December 15, 1903.

Application filed March 31, 1903. Serial No. 150,358. (No model.)

To all whom it may concern:

Be it known that we, JOHN WARREN SMITH and GEORGE UPTON HARN, Jr., citizens of the United States, residing at Columbus, in the 5 county of Franklin and State of Ohio, have invented a certain new and useful Improvement in Printing-Rolls, of which the following is a specification.

This invention relates to the art of printing, 10 and in particular to that type of machine embodying printing and impression rolls.

The object of the present invention is to provide an improved printing-roll wherein provision is made for the convenient setting 15 up and changing of type thereon and for rigidly interlocking the type with the roll, so as to obviate looseness of the former under the action of the operation of the roll.

With these and other objects in view the 20 invention consists in the combination and arrangement of parts, as will be hereinafter more fully described, shown in the accompanying drawings, and particularly pointed out in the appended claims, it being understood 25 that changes in the form, proportion, size, and minor details may be made within the scope of the claims without departing from the spirit or sacrificing any of the advantages of the invention.

Figure 1 is a side elevation of a printing-roll embodying the features of the present invention. Fig. 2 is an enlarged detail sectional view taken on the line $x-x$ of Fig. 1. Fig. 3 is an enlarged detail sectional view on 35 the line $y-y$ of Fig. 1. Fig. 4 is an end elevation of the roll. Fig. 5 is a detail perspective view of one of the type-locking bars. Fig. 6 is a perspective view showing the form 40 of type employed in connection with the present printing-roll.

Like characters of reference designate corresponding parts in each and every figure of the drawings.

In carrying out the present invention there 45 is employed a cylindrical roll, which is solid and preferably of metal, with circular heads 2, secured to opposite ends thereof by means of suitable fastenings 3, the periphery of each head being projected beyond the periphery of a the roll and provided upon its inner face with a cylindrical flange 4, which is greater in diameter

than the roll, and hence overhangs the same and forms an annular groove or seat 5. At regular intervals the projected portions of the heads are provided with corresponding wedge-shaped openings 6, there preferably being four such openings in each head. Adjacent to each of the openings in one of the heads is a shoulder or abutment 7, which is preferably integral with the roll and has its outer face flush with the outer periphery of the head, with one of its ends flush with the radial wall of the adjacent opening 6. Between each abutment 7 and the opposite head an electrotype 8 is fitted. This electrotype is designed to print a standard heading and may be changed whenever desired. A wedge-bar 9 is slid endwise through the adjacent opening in the head and has one end provided with a stud or projection 10 to take into the groove or seat 5 of the opposite head, as best indicated in Fig. 3 of the drawings, thereby to prevent radial displacement of the bar. It will be understood that the engaging faces of the electrotype and the locking-bar 9 are at substantially right angles to the planes of the heads of the roll, while the opposite face of the bar is inclined and designed to bear against the correspondingly-inclined face of a wedge-bar 11, which has been previously introduced through one of the openings in the head and moved around into position for engagement by the locking-bar, it of course being understood that the bar 11 is provided at opposite ends with studs or projections for engagement with the grooves or seats of the heads. To prevent endwise displacement of the locking-bar 9, the outer face thereof is provided with transverse teeth or serrations 12, which are located opposite the abutment 7 and are engaged by the correspondingly-toothed under face of a spring-catch 13 in the form of a spring-plate secured at one end to the electrotype by means of a suitable fastening 14. By reference to Fig. 2 it will be seen that one edge of the electrotype is beveled transversely or undercut, with the adjacent face of the locking-bar 9 correspondingly beveled. The same relation is present between the locking-bar and the wedge-bar.

Each of the individual type 15 is provided with a transverse groove 16 and is designed

to be held between type-holding bars 17, each of said bars being provided with a terminal projection 18 at opposite ends to engage the grooves of the heads 2 and also provided with 5 a longitudinal rib 19 to engage the grooves of the type, and thereby prevent radial displacement thereof. Where it is desired to have a longitudinal space between adjacent rows of type, suitable spacing-blocks 20 are 10 interposed between adjacent type-bars, and these blocks of course have a tongue-and-groove connection with said bars.

Having thus described the invention, what I claim is—

- 15 1. A printing-roll, having opposite heads of greater diameter than the body of the roll, and provided with inwardly-directed cylindrical flanges spaced from the periphery of the roll, the spaces between the periphery of 20 the roll and the flanges forming annular seats or grooves, type-locking bars to fit between the flanges of the heads and provided with opposite terminal reduced projections to enter the grooves of the heads, the projected 25 portions of one of the heads being provided with an opening for the endwise insertion of the type-locking bars and intersecting the grooved and flanged portions of the head.
2. A printing-roll having opposite heads of 30 greater diameter than the body of the roll and provided in their inner faces with annular corresponding grooves, one of the heads being provided with an opening in its projected portion, type-locking bars disposed between the 35 heads and provided with terminal projections slidably received within the grooves, type held between the bars, and a wedge-bar driven through the opening of one of the heads to bind the type-bars upon the type.
- 40 3. A printing-roll, having opposite peripheral flanges, one of which is provided with an opening, type-locking bars fitted between the flanges and having terminal slidable tongue-and-groove connections therewith, type held 45 between the bars, a wedge driven through the opening in one of the flanges to bind the type

between the bars, and means carried by the roll and detachably connected to the wedge to prevent endwise displacement thereof.

4. A printing-roll, having opposite peripheral flanges, one of which is provided with an opening, type-locking bars fitted between the flanges and slidably connected thereto, type held between the bars, a wedge driven through the opening in one of the flanges to bind the 55 type between the bars, and a spring-catch carried by the roll and detachably engaging the wedge to prevent endwise displacement thereof.

5. A printing-roll, having opposite peripheral flanges, one of which is provided with an opening, an electrototype fitted between the flanges adjacent to the opening in one of the latter, type-locking bars fitted between the flanges and slidably connected thereto, type 65 held between the bars, a wedge-bar driven through the opening in one of the flanges and bearing at one side against the electrototype and at its other side against the adjacent locking-bar, the outer face of the wedge-bar being provided with a tooth or serration, and a spring-catch carried by the electrototype and detachably engaging the toothed or serrated portion of the wedge-bar to prevent endwise displacement thereof.

75 6. A printing-roll, having opposite peripheral flanges provided in their inner faces with annular grooves, one of the flanges being provided with an opening, type-locking bars having 80 terminal projections slidably engaging the grooves of the flanges, and also provided with longitudinal ribs or tongues, type held between the bars and provided with grooves receiving the ribs or tongues thereof, and a wedge-bar driven through the opening in one 85 of the flanges to bind the locking-bars upon the type.

JOHN WARREN SMITH.
